CLAIM

The ornamental design for a module for oxygen sensor as shown and described.

DESCRIPTION

1. Module for oxygen sensor

1.1 : Perspective

1.2 : Front

1.3 : Back

1.4 : Left

1.5 : Right

1.6 : Top

1.7 : Bottom

1.8 : Back perspective view

1.9 : Upside-down perspective view

FIG. 1.1 is a diagram illustrating a perspective view of the present design, FIG. 1.2 is a diagram illustrating a front view of the present design, FIG. 1.3 is a diagram illustrating a back view of the present design, FIG. 1.4 is a diagram illustrating a left side view of the present design, FIG. 1.5 is a diagram illustrating a right side view of the present design, FIG. 1.6 is a diagram illustrating a top view of the present design, FIG. 1.7 is a diagram illustrating a bottom view of the present design, FIG. 1.8 is a diagram illustrating a back perspective view of the present design, and FIG. 1.9 is a diagram illustrating an upside-down perspective view of the present design.
